(57) **CLAIM**

The ornamental design for a storage closure, as shown and described.

DESCRIPTION

In a preferred embodiment, the nature of this product is a closure for covering the opening of an enclosure and providing storage space, such as for enclosing the opening of a shower or tub area and storing related items.

FIG. 1 is a right, top, front perspective view of another embodiment of our new design;

FIG. 2 is a right, top, rear perspective view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a top plan view thereof;

FIG. 8 is a bottom plan view thereof; and,

FIG. 9 is a front elevational view of another embodiment of our new design having views that are mirror images of the views shown in FIGS. 1–2 and 4–8;

The broken line representations of wall, door, frame and/or shelving environment in the figures are for the purpose of illustration only, and form no part of the claimed design.

UNITED STATES PATENT AND TRADEMARK OFFICE
CERTIFICATE OF CORRECTION

PATENT NO. : Des. 572,805 S
APPLICATION NO. : 29/282482
DATED : July 8, 2008
INVENTOR(S) : Mike Y. Daikubara et al.

Page 1 of 1

It is certified that error appears in the above-identified patent and that said Letters Patent is hereby corrected as shown below:

On the title page, item (75):

In the naming of the inventors at (75) on page 1, delete all references to Jennifer L. Wenzel, Jody L. Uecke and Steven J. Wietrzny (and their residences and citizenships) as these persons are not co-inventors of this divisional.

Signed and Sealed this

Sixth Day of July, 2010

David J. Kappos
Director of the United States Patent and Trademark Office
